UNITED STATES PATENT OFFICE.

HENRY P. ROBERTS, OF BOSTON, MASSACHUSETTS.

HAIR-DRIER.

1,236,105.

Specification of Letters Patent. Patented Aug. 7, 1917.

Application filed August 18, 1915. Serial No. 46,177.

To all whom it may concern:

Be it known that I, HENRY P. ROBERTS, a citizen of the United States, residing at Boston, county of Suffolk, State of Massachusetts, have invented a certain new and useful Improvement in Hair-Driers, of which the following is a specification, reference being had therein to the accompanying drawings.

10 My invention has for its object the production of a new and improved hair drying device adapted to be used for drying long hair which has become wet through washing or the like. While a number of devices 15 have been produced for this purpose, so far as known to me they have been relatively expensive to produce and inconvenient to operate. The device embodying my invention is of simple construction so that it may 20 be manufactured very cheaply and is so arranged that the heat required while the device is in use may be readily obtained at a negligible cost.

My invention will be fully understood 25 from the following description when taken in connection with the accompanying drawings and the novel features thereof will be pointed out and clearly defined in the claims at the close of the specification.

30 In the drawings, Figure 1 is a side elevation partly in section of a device embodying my invention.

Fig. 2 is a sectional detail enlarged of 35 one of the teeth shown in Fig. 1 secured to a portion of the heater member.

Fig. 3 is a view similar to Fig. 2 showing a modified form of tooth embodying my invention.

Having reference to the drawings there 40 is shown in Fig. 1 a hair drying device provided with a hollow cylindrical member 11 which may be of any suitable heat transmitting material such as tin, aluminum or the like. One end of the cylinder 11 is 45 closed as shown at 12, the other end having a neck 13, a portion of which is provided with spiral corrugations 14 to receive a correspondingly corrugated cap 15 having a suitable washer of cork or the like 16 and 50 adapted to make a tight non-leaking fit with the said neck. The cylinder 11 is provided at one end with a handle 17 of non-heat transmitting material such as wood or the like which may be secured to the cylinder 55 in any suitable way, but in the device shown is secured by means of a U-shaped metallic

strip 18. The metallic strip 18 is soldered to the cylinder 11 and is formed with legs 19 which are adapted to fit tightly within recesses 201 formed in the handle 17 in 60 which they may be secured in any well known manner preferably by adhesive. In the handle 17 is an elongated opening 20 which is so arranged that the heater may be conveniently held to comb and dry the hair 65 without danger of burning the fingers.

The cylinder 11 is provided, preferably on the side opposite to that at which the handle 17 is secured, with an elongated slot or opening 21 shown in Fig. 2. Over 70 the slot 21 a series of hollow teeth 22 are secured by means of a curved back 23 integral with the teeth and adapted to fit over the cylinder 11. The teeth and back are preferably of metal but may be of any other well known heat transmitting material. The back 23 is arranged to entirely cover up the opening 21 and being adapted to fit over a portion of the cylinder 11 may be readily secured to it so that a water tight joint is 80 obtained in any well known manner as by riveting, soldering or the like. By this construction the hollow interior 24 of each tooth is connected with the interior of the cylinder 11. While I have described in detail the 85 construction preferred, I do not wish to limit myself to this form for it is obvious that the teeth may be secured to the cylinder in any well known manner.

The hollow cylindrical heating member is 90 adapted to be filled with hot water which may be readily accomplished by removing the cap 16 and holding the heater under a faucet or the like. The cap is then replaced and the device is immediately ready 95 for use for the hot water instantly heats up the cylindrical heating member 11 and the teeth 22. In practice the device is used as a comb, the hot teeth operating to open up and separate the strands of wet hair and to bring them in contact with the heating member with the result that the hair is dried in a relatively short time. In most cases one filling of water will completely dry the hair, but if it is found that more heat is required, the device may be readily re-filled.

In Fig. 3 is shown a solid tooth 25 which may be used instead of a hollow tooth if desired. When this form of tooth is employed it is not necessary to provide an 110 opening 21 in the cylinder 11 the back 26 being secured to the cylinder and the metal

in the tooth and cylinder acting as a conductor for the heat.

I regard my invention as important for the device embodying it is simple, efficient and both inexpensive to produce and to operate and is so arranged that the heating medium required may be readily obtained. It is not attended with the inconvenience of a cord attachment necessary for the ordinary 10 electrical heating device and is furthermore free from all danger of injuring the hair which is apt to be the case where too high a degree of heat is employed for the boiling point of water is not sufficiently hot to injure hair.

What I claim is:

1. In a device of the character described, a tooth plate having a series of hollow teeth secured thereto, and having a series of perforations which communicate with each of said teeth, a hollow cylinder having an elongated opening in one side, said opening

having a length equal to that of said series of teeth and a width less than that of said plate, and means for securing said plate and cylinder together in a position to enable each of said hollow teeth to communicate with the interior of said cylinder through the said elongated opening.

2. In a device of the character described, a hollow cylindrical member, a series of teeth secured at one side of said cylinder, a U-shaped member secured to said cylinder at the other side thereof with its legs projecting outwardly therefrom, and a hand opening formed therein and having holes at two sides thereof within which the legs of said U-shaped member are received.

In testimony whereof I affix my signature, in presence of two witnesses.

HENRY P. ROBERTS.

Witnesses:
